UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

UPPER BERTH FOR SLEEPING-CARS.

No. 922,850.

Specification of Letters Patent.

Patented May 25, 1909.

Application filed May 27, 1908. Serial No. 435,210.

To all whom it may concern:

Be it known that I, EDWARD G. BUDD, a citizen of the United States, residing at Philadelphia, in the county of Philadelphia and State of Pennsylvania, have invented a certain new and useful Improvement in Upper Berths for Sleeping-Cars, of which the following is a specification.

This invention has reference to sleeping-cars for railways and more particularly to the construction of the upper berths of such cars.

The object of the invention is to provide an improved construction of upper berth, in which the berth is made largely or entirely of metal, so that the structure is fireproof and possesses greater strength than the wooden berths heretofore employed, and with which a mattress of greater thickness may be employed.

20 The preferred embodiment of my invention is illustrated in the accompanying drawings, in which—

Figure 1 is a transverse section through the berth; Fig. 2 is an end view of the frame 25 of the berth; Fig. 3 is a plan view broken away in part; Fig. 4 is a detail view in perspective, of a corner of the frame of the berth; and Fig. 5 is a detail view, in section, on line 5—5 of Fig. 3.

30 Referring to these drawings, 1 indicates the side wall of the car, upon which the berth-frame is pivotally mounted. The frame is of rectangular form and consists of end-members 2 and side-members 3 secured together at their ends, the members 2 being provided with trunnions 4 which are received in bearings upon the side wall of the car to pivotally support the berth in position. The end-members 2 are of angular section, as 35 shown in Figs. 4 and 5, and are curved in the direction of their length, as shown in Fig. 2, so that the berth will have the desired contour. At its ends, each of the end-members 2 is provided with offsets 5 of angular cross-section, as shown in Fig. 4. The side-members 3 of the frame are of angular cross-section, as shown in Figs. 1 and 4, and their ends are adapted to lie close to and to be secured to the offsets 5 by rivets 6. To the rectangular 40 frame thus constructed, is secured a panel 7, of thin sheet-steel, the lateral edges of which are flanged upwardly at 8 and extend up along the outer sides of the side-members 3. These flanged edges are secured to the side-members 3 by rivets 9, so that the securing

means for the panel does not show on the exterior of the berth when the latter is in the closed position. This panel 7, being drawn tightly over the frame of the berth and secured thereto, takes the curvature of the 60 end-members 2 and is entirely free from buckles, so that an attractive appearance is presented. The sheet of metal for the panel 7 is made of slightly greater length than the distance between the non-adjacent faces of 65 the end-members 2, so that when the panel is in position its ends extend a slight distance beyond the end-members 2, as indicated at 10, Fig. 5. In the outer face of each of the end-members 2 are a plurality of shallow depressions, as shown at 11, Fig. 5.

When the panel 7 has been secured to the frame by having its lateral edges riveted to the side-members 3, a plurality of ears 12 of sheet-metal are welded to the panel 7, each 75 directly under one of the depressions 11 and each of a size to fit snugly in the corresponding depression. Each of these ears is then riveted at 16 to the end-member 2 corresponding thereto, in order to hold the end of 80 the panel 7 up close to the lower curved face of the end-member, the ears 12 lying in the depressions in the end-member with their outer faces flush with the outer face of the end-member. In this way, a thin edge of 85 metal at the ends of the panel 7 is provided, projecting a short distance, as, for instance, one-eighth of an inch, beyond the non-adjacent faces of the end-members 2, so that in mounting the berth in position upon the side 90 wall of a car, these projecting edges may be trimmed off as may be required to compensate for variations in the spaces into which the berths are to be fitted.

In practice, it is found that there is some 95 little variation in the length of the spaces for the berths and the parts bounding these spaces are sometimes slightly out of the proper relation; the projecting edges of the panel 7 may be readily filed down, as may be required, so that the panel 7 completely fills the opening for the berth. In these upper berths, it is usual to provide a lock at the center of the berth and near the upper edge thereof, for holding the berth in the closed 100 position, this lock being arranged to reciprocate rods extending lengthwise of the berth and connected at their ends to locking members adapted to be projected into openings in 105 the structure of the car at the ends of the 110

berth. To position these rods and locking members and to guide them in their reciprocating movement, I provide a strip 13, of sheet-metal, extending the entire length of the berth and secured at one of its lateral edges to the outer side-member 3 and at the other edge to the panel 7. Intermediate its lateral edges, this strip is bent as shown in Fig. 1, so as to provide a space between it and the panel 7 to receive the rods and locking members.

The mattress 14 is supported upon the panel 7 and is constructed largely of metal, the spiral springs 15 thereof being made of the maximum length permitted by the thickness of the berth, so that the upper surface of the mattress will be quite soft. The mattress preferably consists of a plurality of sections, so that these may be readily taken out for cleaning and in replacing may be differently arranged, in order that the wear thereon will be uniform. If desired, means may be provided for preventing noise, due to rattling of the parts of the mattress upon the metallic panel 7 supporting the same; this may be done by gluing a sheet of sound-deadening material, as, for instance, heavy asbestos cloth, to the upper face of the panel 7 and extending over the entire surface thereof. By this construction, a berth is provided which is made very largely of metal and which is therefore fireproof. Also since thin sheet-metal is employed to a very large extent, the total weight of the berth is decreased. The employment of a panel of thin sheet-metal permits of employing springs for supporting the yielding surface of the mattress which are of the maximum length permitted by the limitation upon the thickness of the berth, so that the bed will be more comfortable than those heretofore provided. When the berth is in the closed position, an attractive appearance is presented, as there are no rivets showing upon the outer face of the panel 7 and as the panel may be made to completely fill the space provided for the berth.

Having now described my invention, what I claim as new therein and desire to secure by Letters Patent is as follows:

1. In a sleeping-car, the combination of a side-wall, a frame for a berth pivotally mounted thereon consisting of metallic end-members curved in the direction of their length and metallic side-members having their ends secured to said end-members, a panel of sheet-metal extending over said frame and secured at its edges thereto, and a mattress, substantially as set forth.
2. In a sleeping-car, the combination of a side-wall, a rectangular frame pivotally mounted thereon consisting of metallic end-members of angular cross-section curved in the direction of their length to determine the contour of the berth and metallic side-

members of angular cross-section having their ends secured to said end-members, a panel of sheet-steel extending over said frame and secured at its edges thereto, and a mattress, substantially as set forth. 70

3. In a sleeping-car, the combination of a side-wall, a frame pivotally mounted thereon consisting of metallic side- and end-members secured together at their ends, a panel of sheet-metal extending over said frame and secured thereto, said panel extending beyond said end-members of the frame, and a mattress, substantially as set forth. 75

4. In a sleeping-car, the combination of a side-wall, a rectangular frame pivotally mounted thereon consisting of metallic end-members of angular cross-section curved in the direction of their length to determine the contour of the berth and metallic side-members of angular cross-section having their ends secured to said end-members, a panel of sheet-steel extending over said frame and secured thereto, said panel extending beyond said end-members of the frame, and a mattress, substantially as set forth. 80

5. In a sleeping-car, the combination of a side-wall, a frame pivotally mounted thereon consisting of metallic side- and end-members secured together at their ends, a panel of sheet-metal extending over said frame and secured thereto, said panel having flanges at its lateral edges, means for securing said flanges to the side-members of the frame, and a mattress, substantially as set forth. 95 100

6. In a sleeping-car, the combination of a side-wall, a rectangular frame pivotally mounted thereon consisting of metallic end-members curved in the direction of their length to determine the contour of the berth and side-members secured at their ends to said end-members, each of said side-members having a web extending upwardly of the frame and a web lying at an angle thereto, a sheet-metal panel flanged upwardly at its lateral edges extending over said frame, means for securing said flanges to the upwardly extending webs of said side-members, and a mattress, substantially as set forth. 105 110

7. In a sleeping-car, the combination of a side-wall, a frame pivotally mounted thereon consisting of metallic side- and end-members secured together at their ends, a panel of sheet-metal extending over said frame, said panel being flanged at its lateral edges and having its ends extended beyond the end-members of the frame, means for securing said flanges to the side-members of the frame, and a mattress, substantially as set forth. 115 120

8. In a sleeping-car, the combination of a side-wall, a frame for a berth pivotally mounted thereon consisting of metallic end-members curved in the direction of their length and metallic side-members having their ends secured to said end-members, a 125 130

panel of sheet-metal extending over said frame and secured at its edges thereto, a mattress, and sound-deadening material between the mattress and panel, substantially as set forth.

9. In a sleeping-car, the combination of a side-wall, a rectangular frame pivotally mounted thereon consisting of end-members curved in the direction of their length to determine the contour of the berth and side-members having their ends secured to said end-members, a panel of sheet-metal extending over said frame, means for securing the lateral edges of the panel to said side-members, means for securing the end edges of the panel to said end-members, and a mattress, substantially as set forth.

10. In a sleeping-car, the combination of a side-wall, a rectangular frame pivotally mounted thereon consisting of end-members curved in the direction of their length to determine the contour of the berth and side-members having their ends secured to said end-members, a panel of sheet-metal extending over said frame, means for securing the lateral edges of the panel to said side-members, means for securing the end edges of the panel to said end-members, devices secured to said panel and to said end-members for holding the panel to the end-members, and a mattress, substantially as set forth.

11. In a sleeping-car, the combination of a side-wall, a rectangular frame pivotally mounted thereon consisting of end-members curved in the direction of their length to determine the contour of the berth and side-members having their ends secured to said end-members, a panel of sheet-metal extending over said frame, means for securing the lateral edges of the panel to said side-members, ears welded to said panel, means for securing said ears to said end-members, and a mattress, substantially as set forth.

12. In a sleeping-car, the combination of a side-wall, a rectangular frame pivotally mounted thereon consisting of end-members curved in the direction of their length to de-

termine the contour of the berth and side-members having their ends secured to said end-members, a sheet-metal panel extending over said frame and flanged at its lateral edges, said panel having its ends extended beyond said end-members, means for securing said flanges to the side members of the frame, ears welded to said panel and lying in depressions in said end-members, means for securing said ears to the end-members, and a mattress, substantially as set forth.

13. In a sleeping-car, the combination of a side-wall, a frame for a berth pivotally mounted thereon consisting of metallic end-members curved in the direction of their length and metallic side-members having their ends secured to said end-members, a panel of sheet-metal extending over said frame and secured at its edges thereto, a sheet-metal strip running lengthwise of the frame and secured to the inner side thereof to provide a space between it and the panel for locking devices, and a mattress supported upon the frame, substantially as set forth.

14. In a sleeping-car, the combination of a side-wall, a frame for a berth pivotally mounted thereon consisting of metallic end-members curved in the direction of their length and metallic side-members having their ends secured to said end-members, a panel of sheet-metal extending over said frame and secured at its edges thereto, a sheet-metal strip running lengthwise of the frame and having one of its lateral edges secured to the outer side-member and the other lateral edge secured to said panel, said strip being bent longitudinally intermediate its lateral edges to provide a space between it and the panel for locking devices, and a mattress supported upon the frame, substantially as set forth.

This specification signed and witnessed this 20th day of May, 1908.
